(57) **CLAIM**

The ornamental design for a flashlight toy, as shown and described.

DESCRIPTION

FIG. 1 is a front perspective view of our flashlight toy.

FIG. 2 is a front bottom perspective view thereof.

FIG. 3 is a front view thereof.

FIG. 4 is a back view thereof.

FIG. 5 is a right side view thereof.

FIG. 6 is a left side view thereof.

FIG. 7 is a top view thereof; and,

FIG. 8 is a bottom view thereof.

The broken lines are for the purpose of illustrating portions of the article that form no part of the claimed design.
